(57) **CLAIM**

I claim the ornamental design for a device for securing recreational tools, as shown and described.

DESCRIPTION

FIG. 1 is a perspective view of a device for securing recreational tools showing my new design;

FIG. 2 is a front elevational view of FIG. 1;

FIG. 3 is a rear elevational view of FIG. 1;

FIG. 4 is a left-side elevational view of FIG. 1;

FIG. 5 is a right-side elevational view of FIG. 1;

FIG. 6 is a top plan view of FIG. 1; and,

FIG. 7 is a bottom plan view of FIG. 1.

The broken lines in FIG. 7 represent portions of the device that form no part of the claimed design.
